UNITED STATES PATENT OFFICE

170,089

PANEL FOR A LAUNDRY APPLIANCE OR THE LIKE

Walter W. Hoyle, Syracuse, N. Y.

Application December 17, 1952, Serial No. 22,743

Term of patent 14 years

(Cl. D49—1)

To all whom it may concern:

Be it known that I, Walter W. Hoyle, a citizen of the United States of America, residing at Syracuse, in the county of Onondaga, and State of New York, have invented a new, original, and ornamental Design for a Panel for a Laundry Appliance or the like, of which the following is a specification, reference being had to the accompanying drawings, forming part thereof, in which:

Fig. 1 is a plan view of a panel for a laundry appliance or the like showing my new design; Fig. 2 is a longitudinal sectional view thereof taken on line 2—2 of Fig. 1.

Figure 3 is a transverse sectional view on an enlarged scale, taken on the line 3—3 of Figure 1;

Figure 4 is a transverse sectional view on an enlarged scale, taken on the line 4—4 of Figure 1;

Figure 5 is a transverse sectional view on an enlarged scale, taken on the line 5—5 of Figure 1;

Figure 6 is a fragmentary sectional view on an enlarged scale, taken on the line 6—6 of Figure 1.

Figure 7 is a fragmentary enlarged elevational view of the left hand end of the panel; and

Figure 8 is a fragmentary enlarged elevational view of the right hand end of the panel.

I claim:

The ornamental design for a panel for a laundry appliance or the like, substantially as shown.

WALTER W. HOYLE.
